McCOLLUM RUSSELL AND ALFRED G. BURDICK, OF MILL ROCK, IOWA.

Letters Patent No. 70,747, dated November 12, 1867.

IMPROVEMENT IN HAND CORN-PLANTERS.

The Schedule referred to in these Letters Patent and making part of the same.

TO ALL WHOM IT MAY CONCERN:

Be it known that we, McCOLLUM RUSSELL and ALFRED G. BURDICK, both of Mill Rock, in the county of Jackson, and State of Iowa, have invented a new and useful Improvement in Hand Corn-Planters; and we do hereby declare the following to be a full, clear, and exact description of the same, reference being had to the accompanying drawings, which are made a part of this specification:

The subject of our invention is a hand corn-planter, the seed-box of which terminates, at its lower end, in a wedge-shaped point, whose extremity is composed of four converging spring-plates, of steel or other suitable elastic material; two of which are attached to the ends of opposite sides of the grain-box, and the other two to pieces converging from the other two sides, or the converging ends of those sides. The lower ends of these springs, coming closely together underneath the plunger, retain the grains dropped into the chamber, of which they form the bottom, from the pocket in the face of the plunger, so that the descent of the plunger forces them into the ground. In the drawings—

Figure 1 is a transverse section of my improved planter, showing it in the position of having just planted a hill of corn.

Figure 2 is a transverse section, (the plane of which crosses that of fig. 1 at right angles,) showing the position of the planter before the descent of the plunger; and

Figure 3 is a section, on the same plane as fig. 1, of the lower end of the seed-box, showing the position of the front and back springs or scrapers when the plunger is in the position represented by fig. 2.

A represents the seed-box, the elongated sides of which, in connection with the steel springs B B C C attached to them, form a chamber, into which the grain is dropped previous to planting. The bottom and top of the grain-box have each a central opening, for the passage of the plunger E, and the opening in the former is provided with a brush, d, to remove the superfluous grains from the pocket in the plunger which conveys the grain into the lower chamber. The seed-chamber is supplied with grain through the opening, filled by the sliding door F, which is held in place by a button on that side of the box from which it is introduced. The plunger E is operated by the handle G, and its motion is limited by the strap H and stop I. The former of these determines the extent of its upward, and the latter its downward movement. The strap H is also the means by which the box is attached to the plunger, so as to be raised and moved by it. At a suitable distance from the lower extremity of the plunger it is provided with a cell or pocket, e. This pocket is provided with a bevelled bottom, to facilitate its discharge, and its capacity is regulated by the adjustment of the slotted slide J, secured in a recess in the face of the plunger. The extreme lower end of the plunger is bevelled, and covered with iron or steel, as shown in fig. 1, so as to form a metallic point, K. The plunger E may be removed to adjust the slide J by turning the button L, and removing the end of the strap H from the pin h' on which it is hooked.

The operation is as follows: Supposing the several parts in the position represented by figs. 2 and 3, and the pocket e filled with grain from the seed-chamber. By means of the handle G the plunger E is forced down, the brush d removing all superfluous grains from the exterior of the pocket e; and that part of the plunger having passed through the opening in the bottom D of the seed-chamber, brush d, and springs or scrapers B B C C, substantially as and for the purpose set forth.

Having thus described our invention, what we claim as new, and desire to secure by Letters Patent, is—
1. The plunger E, provided with a pocket, e, regulating-slide J, and metallic end K, in combination with the opening in the bottom D of the seed-chamber, brush d, and springs or scrapers B B C C, substantially as and for the purpose set forth.

2. The cell or pocket e, in combination with the regulating-slide J and brush d, substantially as and for the purpose described.

3. The combination and arrangement of the stop I, strap H, pin h', button L, and plunger E, substantially as and for the purpose specified.

To the above specification of our new and useful improvement in hand corn-planters we have signed our hands this 7th day of August, A. D. 1867.

McCOLLUM RUSSELL,
ALFRED G. BURDICK.
